FABRICATED KELLY

Thomas B. Losey, Dallas, Tex., assignor to The
Guiberson Corporation, Dallas, Tex., a corpora-
tion of Delaware

Application July 11, 1947, Serial No. 760,323

8 Claims. (Cl. 255—28)

1

This invention has to do with a rotatable power transmitting conduit employed in the drilling of wells by rotary method; and it is called a fabricated kelly. It differs materially from kellys as ordinarily used in the past, and it presents many improvements thereover.

A primary object of the invention is the elimination of practically all the vibration in a kelly; and another is the complete elimination of "whipping" in the bushings while the kelly is being rotated.

A further important object which has been achieved by this invention is the lessening of the total weight of my kelly as compared to the weight of a conventional kelly required to sustain and drive a drill stem of comparable weight and size. My kelly is at once stronger and lighter.

A primary object achieved by my invention is the complete elimination of the operation of boring a hole through a long rod to form a conduit, such as is practiced in the making of a conventional kelly. It is notorious that these bored holes are extremely difficult to keep straight; and because of the deflection of the bits used in drilling, and the resulting irregularities in the walls of the drilled conduit, the manufacturer of the old kelly always left a considerable amount of stock or thick walls around the drilled holes.

This means that the old fashioned kelly has a smaller conduit, greater friction in fluids forced therethrough (especially in the more viscous fluids) and in a greater pump pressure and more fuel and power costs.

Another important object is the lowering of cost in the making of the kelly. Such costs are cut deeply by the elimination of the expensive, tedious and difficult boring, through solid bars, of the required conduit in the conventional kelly. Further savings in cost are to be found in the elimination of continuous longitudinal welds, such as are sometimes found in another form of conventional kelly. My kelly costs less to manufacture than the drilled kelly or the kelly which is sewed together from end to end with long rows and seams of welding.

One of the most important objects of this invention is achieved in such design and construction as will prevent and eliminate vibration by certain reversals in stress. This situation is brought about by the combination and union of a poly-sided casing and a tubular conduit, the former housing and surrounding the latter, and the natural and periodic vibrations of each

such member being different. A "damping out" of nodes and a severe limitation in the amplitudes of vibration both result from my particular design and construction.

5 A further important object is the elimination of the tendency of the kelly to rupture from internal pressures, there being no break whatsoever in the wall of the stout tubular lining of my fabricated kelly.

10 Another important object and result of my invention is found in the improvement of the skin physicals in the combination of my tubular and poly-sided kelly, as contrasted with the conventional kelly, whether the latter be a drilled kelly, or one in which long seams of welding are used to attach angle irons or channel irons about a tube, as has sometime been done in the past.

15 The lining of my inner conduit is unbroken and undisturbed. No bit has tortured it. No welding seam has been made through its wall.

20 In the shapes of conduits there may be found an added strength (or the lack of it). The most economical sections to afford a required strength 25 to resist bending are (among many) in this order: first, a hollow circular section; and, second, a hollow square section; and I combine both of these designs to achieve the maximum strength and rigidity from a minimum of materials. Such is a valued object.

20 A satisfactory form and embodiment of my invention is disclosed in the accompanying drawings. These are intended to illustrate the principles of construction, the design and method 35 of fabrication, and the relation of the fundamental parts of my invention. However, it must be understood that several modifications and many changes may be made in the structure without departing from the spirit and objects 40 of my invention.

30 For instance, while the drawings show a four-sided casing for my kelly, it should be obvious that this may be made as a five-sided casing, or it may have hexagonal or octagonal external 45 walls. It might well be said, and truly and simply, that I require a poly-sided casing for my kelly.

40 Likewise, the conduit, or internal member of my kelly may be made of any shape or contour which is not identical with the external member. That is to say, while the external member is to be poly-sided, the internal member need not be so made. If poly-sided it should have more sides or less sides than the casing.

45 The ideal situation is a true cylindrical con-

duit within the kelly, and a casing thereabout provided with long, unbroken flat walls, adapted to be passed freely through a hole in the rotary table floor, which hole is to be of corresponding and complementary character. Thus the kelly will be driven when the rotary table turns.

In the drawings, the several figures have been made to present different views of a suitable form of my invention and its associated and related parts, as follows:

Fig. I is an elevational view of my invention suspended on block and hook and in position to be driven by the rotary table.

Fig. II is a partially sectionalized view in perspective of a typical kelly with mid-section removed.

Fig. III is a perspective view of the upper end of a poly-sided casing.

Fig. IV is a perspective view of the lower end of a poly-sided casing.

Fig. V is a partially sectionalized elevational view of the upper part of typical kelly assembly.

Fig. VI is a partially sectionalized elevational view of the lower part of typical kelly assembly.

Fig. VII is a plan view taken along line VII—VII of Fig. V.

Fig. VIII is a plan view taken along the line VII—VII of Fig. V.

Fig. IX is a partially cut-away elevational view of a portion of the mid-section of a typical kelly.

Fig. X is a plan view taken along the line X—X of Fig. IX.

Fig. XI is a plan view taken along line XI—XI of Fig. V.

Fig. XII is a vertical sectional view taken along line XII—XII of Fig. V.

In the drawings the several parts and elements of my invention and the mechanisms incident thereto have been indicated by numerals; and similar parts have been indicated by the same numerals.

In these drawings the numeral 1 indicates a typical rotary table, such as is usually employed in the drilling of wells by rotary method. Such a table is supported by structural members 2, in usual and conventional manner. Driving and driven gears 3 transmit power from drive shaft 4 to the rotary table 1, to rotate the latter.

Conventional power equipment (not shown) operates the drive shaft in the usual way.

The usual stout cable 5 is carried over and by the crown block (not shown) in ordinary manner; and it passes through block 6, having conventional pulleys therein. Such block is provided with hook 7, to support and carry the kelly, the drill stem therebelow and the tools in the hole. When the cable 5 is let out, the drill stem sinks into the bore of the well, and the kelly follows down through the rotary table; and this cable may be drawn up through the block to lift the kelly and the drill stem, all in the usual way.

Stout arms or bails 8 hang on the hook 7, being pivotedly attached to the swivel head 9, the latter being a hollow conventional device communicating with the flexible hose 10, which is a conduit for circulating well fluid from the pumps into the kelly and through the drill stem into the well bore. The pumps are not shown.

A special coupling 11 is made with left hand threads, so that it will not be unscrewed while the kelly is being rotated in the usual fashion to drive the drill stem in the drilling of the hole.

This coupling 11 must be made of very high grade materials, sufficient to stand great stress; and it is internally threaded, so that it may be

used as a connection between the member 9 and the sub 12, which is built into the fabricated kelly 13, the numeral 13 being used to denote the kelly generically. Other numerals are employed to designate the various parts thereof.

The casing 14 of my kelly is preferably made with four or six flat sides. In the drawings, for purposes of clarity, it is simply shown as a square tube. It extends the entire length of the kelly, except for the short subs 12 and 21. These are placed at either end of the sheath 14; and even these subs may be considered as but extensions of the member 14, because they are so completely integrated therein and fixed thereto by appropriate welding, as will be made fully plain hereinafter.

Throughout the entire length of the kelly, and forming a most important and essential part thereof, is the tubular liner 15, preferably having a cylindrical shape. This liner should be made of very high grade steel, perfectly true and straight and with a smooth wall bore.

The external diameter of cylindrical member 15 should be such as will fit with exact nicety into the poly-sided casing 14, touching the latter along the longitudinal center line of each flat wall of such poly-sided member. With this arrangement the external wall of the member 15 may be conveniently fused with and welded to the internal wall of the member 14 through and within numerous spaced welding holes 18, cut in the walls of casing 14. These spaced holes should be made at calculated intervals longitudinally along the median line of each plane surface of the wall of casing 14.

It is recommended (but not required) that where member 14 is provided with either four, six or eight sides, that there be a pair of holes 18 placed through the casing so that they will be directly opposite, the one to the other.

It is further recommended that these successive pairs of holes 18 should be placed and spaced around the wall of member 14 in a "staggered" relation, so that not more than two of such holes (that is to say, one related pair thereof) will ever be found in the same horizontal plane.

The reason for such recommendations is that it is not desired to change, in any manner (more than may be irreducibly inherent in the operation of welding) the characteristics of the walls of either members 14 or 15, in any given horizontal plane; and when two such holes are employed in a common horizontal plane, they should be 180 degrees apart. This maintains an even weight distribution about the vertical axis of the fabricated kelly.

As to the vertical spacing of these holes 18, it is recommended (but not required) that they be spaced apart at least twice the width of the plane on which they appear. That is to say, if the plane face is four inches wide, then the vertical distance between the holes through such face should be at least eight inches.

However, any balanced spacing is permissible so long as the holes are not placed so close as to weaken the wall or materially change its physical characteristics.

In no event should a continuous seam of welding be employed along the mid-line of any plane of member 14. There must not be a welding seam for the entire length of such face. Such is highly undesirable. It results in dynamic unbalance, when the kelly is being rotated. This is so for the reason that long seams of welding material, in an open groove, are not uniform in

mass. Homogeneity, balance and symmetry are lost.

The filling of a single round hole with welding material can be made to result in the placement therein of material of a fixed amount and weight, such as will be found in the proper construction of applicant's invention. This is not true of the longitudinal weld, sometimes heretofore employed by others.

Where a cylindrical liner, as at 15, is fitted snugly into a casing of square cross-sectional area, as at 14, then there will be left and provided about the cylinder the elongated chambers or spaces 24, extending the full length of the casing. These chambers are sealed off at top and bottom, and they do not function as conduits. However, they do operate to promote a difference in vibratory rate and periodicity between members 14 and 15.

It must be borne in mind that the construction of my invention is proper, and the operation thereof is bettered, when the device is fabricated in bilateral symmetry. When so made, my device is both statically and dynamically balanced.

The periodicity in the natural vibration of the poly-sided member 14 is different from that of the circular member 15; and one dampens out the other. The natural nodes in each are not the same. The two are combined to produce a nodiferous tube in which vibration is severely inhibited.

Whenever a tube or casing is described herein as being poly-sided, such description shall be taken to mean that such tube or casing has three or more elongated flat sides of equal area.

Slots 16 are provided in each end of casing 14 to afford space for arcuate sections of the walls of the subs 12 and 21, and to receive welding material 17; and holes 18 in such casing allow for the use of welding material 19 therein.

Where an end of a flat wall of casing 14 is not provided with slot 16 then a compensatory cut may be made across the outer wall of a sub to produce flat face 27 on such sub. An example of such construction is disclosed in Figures IV, VI and VIII.

To make it unnecessary to cut entirely through the wall of a sub when flat face 27 is provided thereon, a slight undercut 25 may be made at the end of liner 15, such undercut being continued a sufficient distance from the end of the liner to accommodate the overlapping sub.

Corner welds 26 are provided for the purpose of uniting a sub with the extreme end of overlapping casing 14 and for the further purpose of completely closing and sealing the ends of the elongated channels or angular spaces 24.

Whenever desired, the slots 16 and the holes 18 may have their side walls uniformly welded to the liner 15 without thereafter filling up the holes and slots with welding material. Such construction will result in a strong kelly, and the balance therein will be maintained by the even nature of the welding in these small and uniform openings.

The angular spaces 24 may be filled with some lightweight material, such as plastic, in order to prevent the leak of fluids under pressure into such spaces, and to preserve balance.

In the design, construction and use of my invention, it is well to bear in mind certain facts, among which the following are important.

It is well to use a cold drawn seamless steel liner for the member 15. Such a tube is of

standard shape and manufacture, and can be procured in a condition where the skin physicals are undisturbed, and where there will be uniformity and integrity in and throughout the wall surfaces of the tube, both inside and outside. This means that I have a very smooth, straight bore throughout the entire length of this tube; and such a condition is very highly desirable, notwithstanding that such is practically impossible to attain through any method other than the one disclosed herein.

Having obtained the proper straight true and undamaged tube 15 I then proceed to complete the fabrication of the kelly as follows:

15 I select a poly-sided tube. Such a tube is a standard production of certain steel mills; and it is usually made by selecting the finest grade of cylindrical tubing (of appropriate wall thickness and metallurgical specifications), then squaring this tube into a four-sided member, having slightly rounded corners. Such a process is carried out through the use of a device called a Turk's-head; and this process results in a perfectly rolled and substantially square member, with undamaged surface and complete integrity of skin physicals.

Much the same process (or any other suitable process) may be employed to produce any desired and specially shaped tubing, whether it be square, hexagonal, or some other poly-sided design.

In the selection of the poly-sided casing member 14, it should be remembered that the cylindrical member 15 should be made to fit snugly within the casing 14, touching the latter on all four sides (where the member 14 is square), and in any case touching it along the central longitudinal line of each of its plane faces.

Before the member 15 is slipped into snug engagement within the casing 14, the latter is provided with a series of "fish mouth" cuts or slots 16. Each such slot begins at the end of the member 14 and proceeds up the side wall thereof a predetermined distance; and all the material within the area of this slot is cut away. Either two or four such slots may be made on each end of a four-sided casing 14.

Under certain circumstances, each alternate flat face of casing member 14 (and at the end thereof) may be provided with a fish mouth cut or slot. When this is the indicated construction, then through the remaining faces (lying between the ones provided with fish mouth cuts) there should be arranged a round drilled hole, such as that indicated by the numeral 18, in Fig. IV. Thus, one face will have a hole therethrough, and the two faces adjoining will each have a fish mouth cut; and each face with a fish mouth cut will be flanked by a pair of faces, each of which will have a hole therein. This makes for balance in weight, welding and strength.

A form of construction in which there are no holes 18 near the end of casing 14 is to be found in Fig. III. This figure simply shows four fish mouth cuts 16, each allowing an exposure of the outer wall of the cylinder 15, for the purpose of making a thoroughgoing job of welding between the two members thus placed.

Regardless of the manner in which member 14 may be attached to the ends (or near the ends) of member 15, there will be a series of spaced holes 18 made through the outer wall of the casing 14, and through each plane face thereof, somewhat in the manner indicated in Figure I. These holes are so positioned, spaced and related that they afford ample openings for welding

members 14 and 15 together at spaced intervals, yet continuously maintaining balance and equilibrium throughout the kelly.

In the making of external welds which connect each sub with the casing it is usual to provide a tapered or rounded shoulder between these members as at 12a. This construction prevents the hanging up of the kelly as it passes upwardly and downwardly through the rotary table.

The subs 12 and 21 (at opposite ends of the kelly) are placed in proper position within the casing 14 and around the tubular member 15, so that all these members may be securely welded together.

Appropriate tools, including special jigs and clamps, hold the materials and parts, thus assembled, in absolutely true alignment; and with them in such position and condition the work of welding is undertaken and completed.

Each hole 18 is carefully welded. The side walls thereof are first fused into the outer surface of the member 15. Then the remaining part of the hole is carefully built up with welding material until the true and original level of the outer face of member 14, through which the hole 18 was drilled, has been reached by being rebuilt with welding material 19. Later all such welded holes, and all welded seams, are polished off, so that such places of weld are very difficult of detection. The spots indicated as holes 18, and welding material 19, on the face of the kelly, as shown in Fig. I, are merely diagrammatic and explanatory.

Each fish mouth cut is carefully built up, by fusing the side walls thereof with the member lying immediately therebelow. After such union is complete and entire, then the remaining space in the fish mouth cut is carefully built up until the outer wall of member 14 has attained its original level. Such face is then ground and polished off so that it presents a true and smooth surface.

Welding 20 is used at each of the ends of the cylindrical liner 15 for the purpose of carefully sewing together the liner and its surrounding sub. Such construction also seals the liner so completely as to prevent the passage of any fluid therebehind.

It should be obvious that any suitable form of connection may be arranged on each end of the kelly; and indicated in the drawings (and used because of its practical nature) will be found suitable threads, such as the male threads 23 on the ends of the kelly, arranged to receive couplings or collars, such as the coupling 11.

The coupling or collar to be used at the lower end of the kelly, will, of course, be of the conventional type, such as is ordinarily used on the standard drill stem. However, the coupling 11, as has been indicated above, should have left hand or reverse threads, so that it will not be unthreaded while the kelly is being driven in the drilling of the well.

The standard drive bushings 22 will be utilized to make contact between the poly-sided kelly 13 and the rotary table 1. These bushings are removable, in the usual way, to allow pipe (with large collars thereon) to be withdrawn through the rotary table, and also for the purpose of substituting slips (in place of the bushings) to hold a string of drill stem, or pipe, from which the kelly has been disconnected.

By fabricating the kelly in the manner hereinabove delineated, including the stitching together of parts by carefully spaced welding, and

the employment of fish-mouthing, and the overlapping of parts, a tremendously strong structure is built up, having a far better than average weight-strength ratio.

5 I claim:

1. In a well kelly, a poly-sided casing having a number of openings through the walls thereof, such openings including holes of uniform area evenly spaced along said walls, and also including a plurality of slots cut through the casing at each of its ends, such openings being so disposed about the vertical axis of said casing as to present a pattern of symmetry; a tubular liner so fitted into said casing as to contact each wall

15 of the latter and extend throughout the casing; means uniting casing and liner, such means including welding by fusion in the region of said openings; a cylindrical extension at each end of said casing and overlapped thereby, and the extension overlapping the liner; each slot being of sufficient scope to receive an arcuate section of an extension; and means provided on each extension whereby the kelly may be removably attached to other well apparatus.

2. In a well kelly, a tubular casing of such shape that a cross section thereof would define a polygon having three or more equal sides, each face of such casing presenting an extended rectangle; openings comprising holes made through

30 the casing wall at spaced intervals along the vertical center line of each such rectangle; openings comprising elongated slots made through said wall and along said line at the ends of a plural number of said rectangles; a cylindrical liner so fitted within said casing as to touch the same along each of said lines, the casing and the liner being welded together at each hole and each slot, and the entire assembly being so arranged about the vertical axis of the liner as

35 to be balanced therearound and to form a plural number of uniform elongated channels arranged between casing and liner, said channels being equally spaced about the latter; and a tubular connector sub extending into said channels and into said slots, the latter being of sufficient width and length to allow the sub to encircle the end of the liner and be overlapped by the end of the casing.

4. In a well kelly, a poly-sided casing having 50 a number of openings through the walls thereof, such openings including holes of uniform area evenly spaced along said walls, and also including a plurality of slots cut through the casing at each of its ends, such openings being so disposed

55 about the vertical axis of said casing as to present a pattern of symmetry; a tubular liner so fitted into said casing as to contact each wall of the latter; means uniting casing and liner, such means including welding by fusion in the region of said openings, the entire assembly being balanced about said axis; a cylindrical extension at each end of said casing overlapping the liner and being overlapped by the casing, the slots being

60 of sufficient size as to permit such overlapping; means for sealing off the ends of the casing at their contacts with said extensions whereby the passage of fluid behind said casing will be prevented; and means provided on each extension whereby the kelly may be removably attached to other well apparatus.

70 4. In a well kelly, a cylindrical liner; a poly-sided casing, so arranged about said liner as to impinge the same and effect intimate contact between the liner and each face of the poly-sided member; each such face having a slotted opening

eliminating such sufficient part of the wall of each such face at the ends of the poly-sided member as to permit in such opening a part of the wall of an attachment sub; an attachment sub projecting into such slotted opening whereby the liner is caused to extend through the sub and the casing is made to overlap it; and means for permanently attaching the subs to the said members so arranged about them.

5. In a well kelly, a tubular liner; a connector sub attached to and overlapping each end of said liner; and a substantially square elongated casing arranged about said liner and in intimate frictional contact therewith, the end of each flat face of the casing being provided with a slot of sufficient area to allow the wall of the sub to extend into said slots and to further allow the angular corners of the casing to overlap the sub.

6. In a well kelly, a cylindrical tube; an elongated square casing so arranged about said tube as to impinge upon the same in a line contact along each inner face of the casing; and a connector sub arranged around each end of the liner, and each such sub being overlapped by the angular corners at the end of the casing, such end being cut away about the median line of each flat face of the casing sufficiently to accommodate therein an arcuate section of the wall of a sub and allow for such overlapping.

7. In a well kelly, a poly-sided casing, the casing being provided with substantially equidistantly spaced slots at each end thereof; a connector sub attached within each end of such cas-

ing, such sub being so constructed and arranged as to provide an arcuate surface thereof extending into said slots; and a tubular liner arranged throughout said casing in intimate frictional contact with the wall thereof, the liner extending into the subs, and the liner and the casing being so related as to provide therebetween a plurality of elongated channels defined by the walls of the liner and the casing, and such channels being sealed against the passage of fluid therethrough.

10 8. In a well kelly, an elongated poly-sided casing having a plurality of slotted openings arranged in each end thereof; a cylindrical liner arranged within the casing and extending therethrough, the external diameter of the liner being sufficient to cause engagement between the liner and the inner faces of the casing; attachment subs overlapping each end of the liner and extending inwardly of the casing, each such slotted opening being sufficient in extent to allow projection of a part of the sub wall therein.

THOMAS B. LOSEY.
